Des. 228,604
Patented Oct. 16, 1973

228,604

FONDUE PLATE

Fred Press, White Plains, N.Y., assignor to
Styson, Inc., New York, N.Y.

Filed July 9, 1971, Ser. No. 161,424

Term of patent 14 years

Int. Cl. D7—01

U.S. Cl. D44—15 C

FIG.1

FIG.2

FIG.3

FIG.6

FIG.4

FIG.7

FIG.5

FIG. 1 is a top plan view of a fondu plate showing my new design;

FIG. 2 is a bottom plan view of said fondu plate;

FIG. 3 is a front elevation view of said fondu plate;

FIG. 4 is a right-side view of said fondu plate;

FIG. 5 is a rear view of said fondu plate;

FIG. 6 is a section view taken along lines 6—6 of FIG. 1; and

FIG. 7 is a section view taken along lines 7—7 of FIG. 1.

I claim:

The ornamental design for a fondu plate, substantially as shown.
